UNITED STATES PATENT OFFICE.

JOHN AUGUST MYERS, OF CLEVELAND, OHIO.

SUPPORTING-RECEPTACLE FOR WATCHES.

1,201,332.

Specification of Letters Patent.

Patented Oct. 17, 1916.

Application filed February 25, 1916. Serial No. 80,468.

To all whom it may concern:

Be it known that I, JOHN A. MYERS, a citizen of the United States, residing at Cleveland, in the county of Cuyahoga and State of Ohio, have invented a new and useful Supporting-Receptacle for Watches, of which the following is a specification.

The present invention relates to an improved case or receptacle for containing 10 watches, and has for an object to provide a device of this character which may be readily attached to the clothing and held rigidly in position against the wearer, so that access may be readily had to the casing 15 and the watch contained therein, without removing the watch, or the casing.

The invention has for another object to provide the improved casing with a novel 20 form of clasp or attaching member for engagement with the garment without injury to the latter, the clasp being of such a nature as to rigidly hold the base or inner section of the receptacle flat against the wearer and prevent it from tilting either outwardly or 25 laterally.

A further and important object of the present invention is to provide a casing which has a lid or cover constituting a hinged section conveniently mounted on the 30 inner section, so that the lid may be swung outwardly from the wearer by one hand, and to so place in the casing, a support for a watch, and provide the casing with novel means for removing that support out of the 35 casing between the lid and the inner portion thereof, to approach a horizontal plane, and thus swing the watch out into such position that it may be comfortably and quickly inspected to ascertain the time, without re- 40 moving the watch from the case or disturbing the adjustment of the latter.

There are various other important features of this invention, which will be hereinafter fully brought out and explained in 45 connection with the specific description of the present preferred embodiment of this invention, the same being disclosed in the accompanying drawings, wherein—

Figure 1 is a side elevation of the improved supporting receptacle closed. Fig. 50 2 is a vertical central section, taken from front to rear through the receptacle. Fig. 3 is a vertical sectional view, taken on the line 3—3 of Fig. 2. Fig. 4 is a side elevational 55 view of the supporting receptacle open, showing the means in operative position to hold the watch extended from the casing and in full view. Fig. 5 is a rear elevation of the receptacle, showing the improved 60 clasp employed for attaching the receptacle to a garment, the dotted lines showing the clasp opened. Fig. 6 is a top plan view of the receptacle closed. Fig. 7 is a horizontal 65 sectional view, taken through the upper end of the receptacle closed, and on the line 7—7 of Fig. 2. Fig. 8 is a detail sectional view, through the locking bail of the clasp, taken on the line 8—8 of Fig. 5. Fig. 9 is a plan view of the tongue employed upon 70 which the watch is mounted. Fig. 10 is an outer face view of the adjustable clamping 75 jaw carried by the tongue for accommodating watches of various sizes. Fig. 11 is an outer side view of the clasp, partly in section, showing one means of attaching the 80 clasp to a garment.

Referring to these drawings, wherein like parts are designated by similar characters of reference throughout the several views, 85 10 designates the bottom or inner section of the receptacle, which is in the form of a flat plate adapted to be vertically positioned against a garment in front of the wearer and within easy reach of the hands. This flat plate 11 is reinforced at its lateral edges by outwardly extending vertical flanges 11, which, as shown to advantage in Fig. 7, are strengthened by returned diagonal brace portions 12 extending inwardly and engaging 90 at their inner ends against the outer face of the plate 10. In Fig. 4, the lower ends of the flanges are clearly shown as being rounded, as at 13. The upper edges of the flanges 11 are preferably straight and lie in a horizontal plane. The upper end of 95 the base or bottom plate 10 is provided with a bracket 14 in the form of a flat strip secured across the inner face of the plate 10 near the upper edge thereof and having an overturned depending flange 15 at its upper 100 edge to which are pivotally connected the upper ends of a pair of laterally spaced apart clasp arms 16. As shown to advantage in Fig. 5, these arms 16 are relatively 105 long, are hinged upon pivots 17 projecting rearwardly from the flange 15, and lie flat against the flange 15. The arms 16 extend downwardly to a point adjacent or near to the lower edge of the base plate 10 and are so pivoted as to hang in parallelism with 110

each other, and in slightly spaced apart relation. Notches 18 are formed in registering pairs in the inner edges of the arms 16 to accommodate buttons, or other projections or devices which may be attached to the garment, and which may be utilized in firmly securing the improved structure thereto. The arms 16 are adapted to be spread apart laterally, as shown in dotted lines in Fig. 5. A portion of the garment is gathered in a vertical direction and placed in between and against the longitudinal edges of the spread apart arms 16. The arms are then forced together as shown to advantage in Fig. 11, and are held in closed position against the gathered portion of the garment by a locking bail 19. The locking bail 19, as shown to advantage in Fig. 8, is of U-shape, the opposite arms of which are hingedly connected to and held flat against the opposite sides of one of the arms 16 by means of a rivet, or other suitable pivot pin 20. The closed or bridge portion 21 of the bail is provided with an inner flat face adapted to engage against the outer vertical edge of the opposite arm 16 to thus frictionally hold the bail 19 on the arm and prevent the dropping of the bail. A finger piece 22 projects upwardly and outwardly from the closed end of the bail 19 to admit the easy forcing down of the bail and lifting of the same in applying and removing the receptacle. The intermediate and lower portions of the base section 10 of the receptacle are enlarged edgewise or laterally, so as to impart to the receptacle, in a general way, the contour of the watch, and so as to admit of the placing of the watch in the receptacle. This formation is given to the main section 10 by curving outwardly the flanges 11 as at 23, and correspondingly broadening the base plate 10 to entirely close the back of the receptacle as may be best seen in Fig. 5.

A link 24 is hinged by rivets 25 to the lower end of the main section 10. The link is disclosed in the present drawings, as in the form of a flat plate, of a width equal to the width of the lower end of the main section 10, and which has lateral upstanding flanges 26 of a depth equal substantially to the depth of the flanges 11, and provided at one end of the link with inwardly offset ears 27 adapted to lie flat against the inner sides of the flanges 11, as shown to advantage in Fig. 3. The rivets 25 hingedly connect the ears 27 to the flanges 11 and thus hingedly support the inner end of the link 24 upon the lower extremity of the main section 10. The ears 27 are of such length, and the rounded edges 13 of the flanges 11 are such as to admit of the free swinging of the link about the pivots 25 to bring the inner edge of the link 24 flat against the lower edge of the base section or plate 10, as shown in Fig.

5. The forward end of the link 24 has its flanges 26 rounded, as at 28, to bear against the lower edge of the lid 29 or outer section of the receptacle. The lower edge of the lid is adapted to slide against the rounded outer ends 28 of the link flanges, and the bottom plate or body portion of the link 24 is curved upwardly, as at 30, to meet the lower edge of the lid 29 and provide, in all adjustments of the lid and the link, a sealed joint therebetween. The lid 29 is in the form of a sheet metal plate which is slightly bulged or convexed, as shown in Figs. 1, 2, 6 and 7, to impart a fanciful and attractive configuration to the receptacle, and also to accommodate the watch, which is placed in the receptacle. The plate or lid 29, has lateral inturned flanges 31, which extend from top to bottom of the lid or plate 29, and which project downwardly to a slight extent below the plate 29 to form ears 32, which lap over against the opposite outer sides of the flanges 26 of the link. Pivots 33 are secured through the ears 32 and the lower rounded ends of the flanges 26, and are in the form of rivets, to unite the lid to the link and admit of the hinging of the lid on the link. By this structure, it is seen that the main section 10 is connected to the lid or cover section 29 by a double hinged joint provided by the pivotal mounting of the opposite ends of the link 24 to the respective lower ends of the base section 10 and the lid section 29.

When the lid section 29 is closed or moved inwardly against the base section 10, the link 24 is swung down toward the vertical plane of the main section 10, as shown in Figs. 1 and 2, and its downward swinging movement is limited by the abutting edges 34 of the main section and the link. The lid section 29 is of a width to overlap the flanges 31 thereof against the outer sides of the flanges 11 of the main section. The lid 29 is provided upon its upper end with a closure wall 35, which extends across the upper ends of the flanges 31 and which projects rearwardly beyond the rear edges of the flanges 31. This overhanging portion of the wall has a depending flange 36 across its rear edge which meets at its ends the lateral flanges 37 which comprise continuations of the upper ends of the flanges 31, and which depend from the lateral edges of the top wall 35. This structure provides a rearwardly extending lip adapted to engage over and snugly receive the upper end of the section 10, as shown in Figs. 1 and 2, to hold the lid section 29 from swinging outwardly, and thus close the case.

The upper end of the lid section 29 is provided with a handle 38, which is disclosed in the present instance as being of substantially T-form, and having the shank thereof curved backwardly at its upper end. The lower end

of the shank is bifurcated to provide a pair of ears 39, receiving therebetween, an upwardly ear or stud 40. The stud 40 is hingedly connected between the ears 39 by a pivot pin 41. The stud or ear 40 rises from a relatively small plate 42, which is suitably secured upon the upper face of the wall 35, which closes the top of the lid section 29. By providing a handle 38 of T-form, the same may be readily grasped by the fingers to elevate the lid section 29 and lift the supporting lip thereof over the top of the inner section 10.

The watch 43 is supported in the receptacle upon a tongue 44, which is hingedly connected at its upper end to a plate 45 welded, or otherwise suitably secured against the inner face, and at the upper end of the outer wall of the lid section 29. The plate 45 is provided, as may be best seen from Figs. 2, 3, 4 and 9, with a plurality of tongues or projections, which are rolled over and which are arranged in transversely spaced relation to provide spaced apart eyes 46, receiving therebetween correspondingly formed eyes 47 on the upper end of the tongue 44. Thus, the tongue 44 is hingedly mounted in the top of the lid section 29 by a transverse pintle 48, which passes through the registering eyes 46, 47 on the upper end of the tongue 44. The tongue 44, as may be best seen from Fig. 2, is curved longitudinally to conform to the inner curvature of the front wall 29, so that the tongue may lie close thereagainst. The outer extremity of the tongue, which is the lower end thereof, has an inturned stop flange 49 adapted to receive thereagainst the outer end of a finger 50, which is rigidly mounted upon the link 24, and adapted to be swung thereby outwardly against the inner face of the tongue, and to slide thereover into abutting relation with the stop flange 49. In Fig. 4, the finger 50 is shown in an outwardly swung position and adjacent to the stop flange 49. The flange 49 merely limits the outward swinging of the finger beyond the end of the tongue 44, so that when the receptacle is closed, the finger may be automatically retracted. This finger 50, as shown in Fig. 3, is in the form of a flat metallic spring strip having its lower end bent U-shaped, and returned beneath the same, as shown in Figs. 2 and 4, and being welded, or otherwise suitably secured against the inner face of the link 24. The finger 50 rises from the link 24 at a point substantially in alignment with the transverse axis of the pivots 33, which connect the lid section 29 to the link 24, so that the finger 50 swings substantially about the axis of the pivots 33. The outer end of the finger 50 is flat and adapted to slide against the inner face of the tongue 44 to project the tongue from the

closed position, shown in Fig. 2, into the open position shown in Fig. 4.

The tongue 44 is provided near its upper end with a pair of transversely spaced apart jaw members 51, which are preferably cut and stamped from the lateral edges of the tongue 44, bent upwardly, and curved, so as to present concaved faces to the outer end of the tongue. As shown in Fig. 9, these jaw members are in the form of upstanding fingers, which provide a fixed jaw upon the upper end of the tongue, which jaw has a socket opening 52 therein to receive through the opening 52 the stem 53 of the watch 43. The watch 43 is adapted to lie flat upon the outer face of the tongue 44 below the upper jaw members 51. The lower end of the tongue 44 carries an upstanding threaded stem 54 which projects through a longitudinal slot 55 formed in the base section 56 of a movable jaw 57. The jaw 57 is bent substantially at right angles to provide the base portion 56 adapted to slidably engage the outer face of the tongue 44. The upstanding portion of the jaw 57 is curved transversely to present a concaved face for engagement with the lower end of the watch 43, opposite to the stem 53. To prevent injury to the watch, and to prevent vibration thereof, in the receptacle, a packing 58, of rubber, or the like, is fitted upon the tongue between the jaws, the packing extending up against the inner opposite faces of the jaws 51 and 57, so as to practically entirely house the sides and the back of the watch. A thumb nut 59 is threaded upon the upper end of the stem 54 and binds downwardly against the base portion 56 of the adjustable jaw 57 to hold the latter in its adjusted position. Thus, the jaws are adapted to receive therebetween, a watch of practically any size and to securely clamp the watch upon the tongue.

In Fig. 11, the arms 16 of the clasp are shown in engagement with a portion of material 59^a, the material being gathered or doubled and placed between the arms 16, and the latter being swung toward each other and held in binding engagement against the opposite sides of the material by the bail 19. For the purpose of preventing any accidental slipping or dislodgment of the material 59^a, a plurality of pins 60, or the like, may be passed through the material at the inner sides of the arms 16, so that should the material slip outwardly between the inner edges of the arms 16, the pins 60 would strike against the inner sides of the arms and thus hold the material from further displacement.

In the use of the supporting receptacle of this invention, a watch 43 is clamped upon the tongue 44 between the jaws 51 and 57. The lid section 29 is swung inwardly about

its double hinged link 24 against the base section 10, the lid section being moved against the base section with a downward movement to engage the supporting lip over 5 the upper end of the base section. Thus, the lid section 29 is hung upon the base section 10, and the meeting edges of the lower wall of the base section and the upper wall of the link 24 are so disposed that they abut 10 when the base and lid sections are interlocked to seal the rear side of the receptacle. It will also be noted that the curved wall 32 at the forward end of the link 24 is of such length that when the lid section 29 is in vertical 15 position and supported upon the base section 10, the lower end of the wall of the lid 29 seals the lower extremity of the receptacle when closed.

When it is desired to examine the face of 20 the watch to ascertain the time registered thereby, the wearer grasps the handle 38 and exerts an upward and outward pull upon the same. As the handle 38 is pivoted, it automatically adjusts itself to the fingers 25 of the operator, so that the device may be comfortably handled. The handle 38 is moved outwardly and upwardly, so as to lift the lid section 29 to disengage the locking lip thereof from the base section 10. The 30 lid section 29 is now moved further outwardly and held in its raised position, so as to lift the outer end of the link 24 and swing the link about its inner pivot 25. Such action swings the lid section 29 outwardly at substantially right angles to the link 24. Such relative movements of the link 24 and the lid section 29 causes the finger 50 to move outwardly from the inner wall of the lid section and bear against 35 the inner side of the tongue 44 to swing the latter outwardly into the position shown in Fig. 4. This figure shows the normal position of the finger 50, the stop flange 49 merely serving as a means for preventing 40 the accidental passage of the finger 50 beyond the end of the tongue 44, which action would release the tongue from the finger and allow the tongue to swing back into the lid section 29. The finger 50 thus projects 45 the tongue outwardly from the lid section 29 and moves the watch 43 from substantially a vertical position into an inclined position, which approaches a horizontal plane, so that 50 the face of the watch may be easily and readily inspected by looking downward into 55 the open receptacle. In closing the receptacle, the lid section 29 is first moved inwardly to swing the link 24 thereagainst to some extent, and thus release the tongue 44, 60 and admit of its swinging backwardly into the lid. The lid is supported upon the handle 38, and is carried back and hooked over the upper end of the base section. The clasp carried upon the back of the base section 65 extends longitudinally thereof, and en-

gages the garment of the wearer throughout a considerable distance. Thus, when the base section is secured in upright position upon the garment, it is firmly held in such position by the long vertically positioned clasp and the receptacle is thus held from tilting or twisting laterally.

By the provision of the adjustable jaw 57, watches varying in size may be conveniently secured in the receptacle. By opening the lid section 29, the same is moved outwardly from the base section to a considerable extent, so that the interior of the lid may be thoroughly inspected. Furthermore, the improved supporting and tilting device within the receptacle projects the watch outwardly from the lid section and raises it into a suitable angle from which the watch may be easily inspected.

It is, of course, understood that it is within the spirit of this invention to modify or change the above specifically described structure within the scope of the claims, in order to adapt the device to various designs and materials which may be used, and to any other desired articles which are to be carried by a person and held in a convenient place for ready inspection.

What is claimed is:

1. A supporting receptacle for watches comprising a base section, a clasp on the base section for engagement with the garment of the wearer, a lid section adapted for engagement over the base section and to be supported thereby, a watch support hinged at its upper end in the lid section and adapted to lie therein, a link connecting the lower end of the base section with the lower end of the lid section, and a finger fixed upon the link and projecting upwardly into the base section against the inner side of the watch support, said lid section being adapted to be swung outwardly from the link, whereby to move said finger outwardly against the watch support, and swing the latter outwardly from the lid section.

2. A supporting receptacle for watches comprising a base section for securing to the garment of the wearer, a lid section hingedly connected to the base section, a watch support inclosed in said sections, and means operable upon the opening of the lid section to project said watch support at an angle outwardly between the sections.

3. A supporting receptacle for watches comprising a base section, a clasp carried at the back of the base section and adapted for securing to a garment, a lid section provided with a rearwardly extending lip adapted for engagement over the upper end of the base section to support the lid section, a link joining the lower ends of the base and lid sections, a tongue hinged in the upper end of the lid section, an adjustable clamp on the tongue adapted to receive

watches of various sizes, and a finger on the link engaging the tongue to project the lower end of the latter outwardly from the lid section and toward the base section, 5 whereby to position the watch across the space between the base and lid sections.

4. A supporting receptacle for watches comprising a base section, means for securing the base section vertically against the 10 front of a garment, a link hinged at one end upon the lower end of the base section, a lid section hinged to the outer end of said link and extending upwardly therefrom, a rearwardly extending lip upon the lid section 15 adapted for engagement over the top of the base section to support the lid section thereon, a watch support hinged in the receptacle, and a connection between the link and the watch support to tilt the latter 20 outwardly between the base and lid sections upon the opening of the latter.

5. A supporting receptacle for watches comprising a vertical plate, a link hinged to the lower end of the plate, a lid section 25 hingedly connected to the link and adapted to support a watch therein and having a lip upon its upper end for engagement over said vertical plate, a bracket secured against the back of the plate near its upper end, 30 opposed flat arms pivoted to the bracket and adapted to hang down against the opposite sides of a gathered portion of a garment, and in spaced relation to said plate, and a bail hinged upon the lower end of one 35 of the arms and adapted to be swung upwardly over the end of the opposite arm to hold the arms from spreading apart, and in binding relation against said gathered portion whereby to support the receptacle 40 on the garment.

6. A supporting receptacle for watches comprising a vertical plate, a link hinged to the lower end of the plate, a lid hinged to said link and provided with inwardly 45 extending sides, a hinge plate secured in the upper end of the lid section, a strip arranged in the lid section, to provide a tongue therein and normally lying flat in the lid section, said tongue and said hinge plate 50 having interfitting eyes upon their upper ends, a pintle engaging through the eyes to hingedly connect the tongue to the hinge plate, a stop flange extending inwardly from the lower extremity of the tongue, a fixed 55 finger carried by the link for engagement against the inner face of the tongue to swing the latter outwardly when said lid section is moved away from said vertical plate, a pair of spaced apart jaw members struck 60 from the upper end of the tongue to engage the upper edge of a watch and receive a watch stem therebetween, a movable jaw slidably mounted upon the lower end of the tongue to engage the lower end of the watch, 65 a binding nut carried by the tongue for en-

gagement with the movable jaw to secure it in adjusted position, and a packing carried by the tongue between said jaws for engagement against the watch to protect the same.

7. A supporting receptacle for watches comprising a base section, a lid hingedly connected to the base section at its lower end, a lip on said lid for engagement over the upper end of the base section to support the 70 lid, and a T-shaped handle pivoted at the lower end of the shank thereof upon the top of said lid, and having the shank curved backwardly to dispose the head of the handle flat against the top of the receptacle and 75 in position for ready engagement by the fingers.

8. A supporting receptacle for watches comprising a base section, a clasp on the base section for engagement with the garment of the wearer, a lid section adapted for engagement over the base section and to be supported thereby, a watch support hinged at its upper end in the lid section 85 and adapted to lie therein, a link connecting the lower end of the base section with the lower end of the lid section, and means whereby when the lid section is swung outwardly away from the base section, the watch support is projected at an angle 90 between the two sections.

9. A supporting receptacle for watches comprising a base section, a lid section adapted for engagement over the base section and to be supported thereby, a watch 100 support in the lid section and adapted to lie therein, a link connecting the lower end of the base section with the lower end of the lid section, and a finger between the link and the watch support, said lid section being 105 adapted to be swung outwardly from the link, whereby to move said finger outwardly against the watch support, and swing the latter outwardly from the lid section.

10. A supporting receptacle for watches comprising a base section, a lid section provided with means adapted for engagement over the upper end of the base section to support the lid section, a link joining the lower ends of the base and lid sections, a tongue hinged in the upper end of the lid section, an adjustable clamp on the tongue adapted to receive watches of various sizes, and a finger on the link engaging the tongue to project the lower end of the latter outwardly from the lid section and toward the base section, whereby to position the watch across the space between the base and lid sections.

11. A supporting receptacle for watches comprising a base section, a link hinged at one end upon the lower end of the base section, a lid section hinged to the outer end of said link and extending upwardly therefrom, means upon the lid section adapted 120 125 130

for engagement over the top of the base section to support the lid section thereon, a watch support hinged in the receptacle, and a connection between the link and the watch support to tilt the latter outwardly between the base and lid sections upon the opening of the latter.

12. A supporting receptacle for watches comprising a base section, a lid section adapted for engagement over the base section and to be supported thereby, a watch support hinged at its upper end in the lid section and adapted to lie therein, a link connecting the lower end of the base section with the lower end of the lid section, and means connecting the watch support and link whereby when the lid section is swung outwardly away from the base section, the watch support is projected at an angle between the two sections.

13. A supporting receptacle for watches, comprising a base section, a lid section, a link pivotally connecting the two sections together, a watch support mounted within the lid section and adapted to lie therein, said lid section being adapted to swing on the pivots of the link to assume a position substantially at right angles to the link, and means operable upon the opening of the

lid section to project the watch support at an angle between the two sections.

14. A supporting receptacle for watches comprising a base section, a lid section, means pivotally connecting the two sections together, a watch support mounted within the lid section and adapted to lie therein, said lid section being swung on said pivotal means to assume a position at an angle to the base section, and means operable upon the opening of the lid section to project the watch support at an angle between the two sections.

15. A supporting receptacle for watches comprising a base section, a lid section, a watch support within the lid section, a link connecting the lower end of the base section with the lower end of the lid section, and means whereby when the lid section is swung outwardly away from the base section, the watch support is projected at an angle between the two sections.

In testimony, that I claim the foregoing as my own, I have hereto affixed my signature in the presence of two witnesses.

JOHN AUGUST MYERS.
